FARNUM F. DORSEY, OF ROCHESTER, NEW YORK, ASSIGNOR TO NORTH EAST ELECTRIC COMPANY, OF ROCHESTER, NEW YORK, A CORPORATION OF NEW YORK.

POWER-TRANSMISSION MECHANISM.

1,140,132.

Specification of Letters Patent. Patented May 18, 1915.

Application filed May 28, 1913. Serial No. 770,527.

To all whom it may concern:

Be it known that I, FARNUM F. DORSEY, a citizen of the United States, and resident of Rochester, in the county of Monroe and State of New York, have invented certain new and useful Improvements in Power-Transmission Mechanism, of which the following is a specification.

This invention relates to power-transmission mechanism whereby two rotary shafts or elements may be connected so that either one of them may actuate the other, the mechanism operating in such a manner as to produce different speed-ratios between the elements, according as one or the other is acting as the driving-element.

Mechanisms of the type in question are employed in connection with the machinery of motor-vehicles, for the purpose of connecting an electric generator with an internal-combustion engine, so that the generator may normally be driven by the engine, to charge a storage-battery or provide electric current for other purposes, while, on the other hand, the generator may be utilized as an electric motor to provide power for starting the engine from a condition of rest, and it has previously been proposed to render mechanism of this kind automatic in its operation by the use of automatic unidirectional connecting-devices, such as roller-wedge clutches, these clutches serving, on the one hand, to cause the engine-connected element to rotate the generator-connected element directly, or, on the other hand, to cause the latter element to rotate the engine-connected element, at a lower speed, through speed-reducing gearing.

Owing to the fact that the normal direction of rotation of both the rotary elements is always the same, whether one or the other acts as the driver, the arrangement of the one-direction clutches which is necessary for the performance of their normal functions results, incidentally, in a tendency to a locking action which prohibits reverse rotation in the engine-connected element. This is objectionable, where the gearing is used in connection with an internal-combustion engine, for several reasons, one of these reasons being that the engine when running normally at low speed, or when being started from a condition of rest, is liable to premature ignition, resulting in "back-kicking" or reverse rotation, and if the trans-

mission-mechanism is so constructed as to rigidly resist such backward rotation, its parts are subjected to a severe strain. Furthermore, it is desirable that the engine, when coming to rest after being in operation to drive the vehicle, be permitted to turn backwardly to a sufficient degree to permit its pistons to assume their normal position of rest or equilibrium in the engine-cylinders, as the engine, when its parts are in this position, may frequently be started by mere manipulation of the ignition-devices, and without the necessity of employing the electric generator for that purpose.

The object of the present invention is to produce a power-transmission mechanism, of the type in question, in which the operation may be partly or wholly automatic, but in which provision shall be made for automatically unlocking the gearing against reverse rotation on the part of the engine-connected element. To this end I employ, in addition to the two rotary elements before mentioned, a third rotary element, which constitutes a part of the connections through which the first two elements are operatively connected, and which normally rotates with one of these elements, but which is also capable of a limited rotation with respect to such element. This third rotary element is connected, in turn, with one of the clutches by which power is transmitted from one to the other of the first two rotary elements, in such manner that upon a tendency to reverse rotation in the engine-connected element the clutch in question is automatically thrown or held out of operation, as a consequence of the relative motion before mentioned, so that the mechanism is unlocked, and the engine-connected element is permitted to rotate freely in the reverse direction.

In the accompanying drawings:—Figure 1 is a vertical sectional view of power-transmission mechanism embodying the present invention, in the plane of the axes of the several rotary elements; and Fig. 2 is a partly sectional view, on the line 2—2 in Fig. 1, looking from right to left in the latter figure and showing particularly the arrangement of the one-direction clutches.

In the illustrated embodiment of the invention a rotary element or shaft 5, which is hereinafter referred to as the "first rotary element," is mounted in ball-bearings 6 in a casing 7, this shaft 5 being adapted for con-

nection with the crank-shaft or other rotating part of the engine in connection with which the mechanism is to be used. A second shaft or rotary element 8, which is hereinafter referred to as the "second rotary element," is also mounted in the casing 7, being supported, near one end, by a ball-bearing 9, while its inner end has a reduced part 10 which turns in a central recess in the shaft 5, the two shafts being thus held in axial alinement. The shaft 8 may be connected with the armature-shaft of the electric generator in connection with which the mechanism is used, and for this purpose, its right-hand portion 14 is squared for the attachment of one member of a coupling 11. This coupling, which is illustrated as of the well-known Oldham type, connects the shaft 8 with the armature-shaft of a generator, of which only the end of the casing 12 is shown in Fig. 1, the generator-casing being rigidly connected with the casing 7 by means of a bracket 13.

The automatic one-direction clutches of the present mechanism are arranged at the right-hand end of the shaft 5, this part having an enlargement or shell 15 which constitutes members of both clutches. The cylindrical inner surface of the shell 15 is engaged by rollers 16, which are seated in recesses in an inner clutch-member 17 integral with the shaft 8. These recesses, as shown in Fig. 2, are so inclined at the bottom that when the shaft 5 and the shell 15 are rotated in the direction indicated by the arrows in Fig. 2, which is the normal direction of rotation, the rollers 16 are moved toward the shallower parts of the recesses, so that they are wedged against the clutch-surface on the part 15, and the shaft 8 is thus rotated in unison with the shaft 5, for the purpose of actuating the electric generator. This action of the rollers 16 is insured by means of spring-pressed followers 18 located in the recesses and constantly pressing against the rollers.

When the shaft 8 is to constitute the driving-member, in the operation of starting the engine, power is transmitted from this shaft 50 to the shaft 5 through speed-reducing gearing. This gearing comprises a pinion 19 on the shaft 8, and a gear 20 with which the pinion 19 meshes, this gear being mounted to rotate about a fixed counter-shaft 21 in 55 the casing 7. The gear 20 is connected, in turn, with a pinion 22, which meshes with a gear 23 concentric with the shell 15. The gear 23 is annular in form, and its smooth inner surface 24 constitutes an element of a 60 second roller-wedge clutch, being engaged by rollers 25 which are seated in recesses 26 formed in the periphery of the shell 15, as shown particularly in Fig. 2. These recesses are so inclined, at the bottom, that 65 when the gear 23 is rotated in the direction

indicated by the arrows in Fig. 2, the rollers 25 move toward the shallower parts of the recesses, thus being pinched between the clutch-members, and causing the shell 15 and the shaft 5 to be rotated by the gear 23. 70

It will be apparent that whenever the first rotary element is driving the second rotary element, the latter may overrun the former in the normal direction of rotation, since the rollers 16 will, in this case, slide freely 75 within the shell 15, while on the other hand the first rotary element, when being driven through the speed-reducing gearing by the second rotary element, may also overrun freely when, for example, the engine has 80 started its normal operation, owing to a similar action on the part of the rollers 25. When the first rotary element tends to rotate in the reverse direction, however, in consequence of a back-kick in the engine with 85 which it is connected, this rotation is transmitted to the gear 23, and thence, through the other parts of the speed-reducing gearing, to the pinion 19, and if this pinion were 90 rigidly attached to the shaft 8 this tendency to reverse rotation on the part of the pinion would be resisted through the action of the inner roller-wedge clutch, since this clutch would prevent the second rotary element 95 from rotating in a reverse direction faster than the first rotary element.

To avoid the locking action just referred to I employ, in the illustrated mechanism, as the third rotary element hereinbefore referred to, the pinion 19, this pinion being 100 mounted loosely upon the shaft 8, so that it may have a limited rotation relatively to the shaft. Integral with the pinion 8 is a flange 30, from which three fingers 31 project into the corresponding recesses in the 105 clutch-member 17. As shown particularly in Fig. 2, each of the fingers 31 is adapted to move freely, to a limited extent, within the corresponding recess, in such a manner that it may engage and move one of the rollers 16. When the engine is operating in the normal direction of rotation the pinion 19 is free to rotate in the same direction, and at the same speed as the shaft 8, the frictional tendency of the parts being to 110 promote such rotation, although the gears are not at this time in useful operation, and thus the fingers 31 do not interfere in any way with the operation of the rollers 16 under the influence of their spring-pressed 115 followers and the wedging tendency of the co-operating clutch-surfaces. Accordingly, at this time the fingers 31 rotate idly with the other parts and perform no function. Under these circumstances, however, if the direction of rotation of the shaft 5 be reversed, in consequence of a back-kick in the engine, or of the tendency of the pistons of the engines to come to rest in an intermediate position when the engine is stopped, 120 125 130

the gear 23 is rotated reversely, as before stated, in consequence of this movement of the shaft 5, and it produces a corresponding rotation, at higher speed, on the part of the pinion 19. In this manner the fingers 31 are forced backwardly against the rollers 16, so as to press them toward the deeper ends of the recesses in the clutch-member 17, and throw the clutch out of operation. The fingers then, by their pressure against the rollers, which is transmitted, in turn, to the clutch-member 17, may rotate the shaft 8 freely in the reverse direction, thus permitting the mechanism to accommodate itself 15 to the tendency of the engine to rotate backwardly.

When the shaft 8 constitutes the driving member, in the operation of starting the engine by power derived from the generator, the shaft 8 rotates the clutch-member 17 in the normal direction, and this rotation is transmitted, through the rollers 16 and the fingers 31, to the pinion 19, and thence, through the other parts of the gearing and 25 through the outer clutch, to the shaft 5. Accordingly, the pinion 19 rotates in unison with the shaft 8 and drives the gearing in substantially the same manner as if it were fixed to that shaft. In this connection, however, the present invention has a further utility, in that the driving-pressure transmitted through the rollers 16 to the fingers 31 causes these rollers to be held back, in opposition to the pressure of their spring-pressed followers 18, so that the pressure of 35 the rollers against the clutch-surface of the shell 15 is relieved, and the friction which would otherwise occur between these parts is eliminated. This effect may be increased by beveling the sides of the fingers 31, as 40 shown in Fig. 2, in a direction to force the followers inwardly rather than outwardly.

While the unlocking-mechanism just described permits the shaft 8 and the generator to be rotated in the reverse direction when necessary, it does not relieve the mechanism from a strain which may arise, owing to the momentum of the armature of the generator, when the rotation of the engine is suddenly 45 reversed while the generator-armature is rotating at high speed in the normal direction. Accordingly, it is preferable to interpose, at some point between the shaft 5 and the generator-shaft, a yielding or frictional connection which will permit the generator-shaft to be brought gradually to rest, and then thrown into reverse rotation, when the direction of rotation of the shaft 5 is suddenly and powerfully reversed. Such a 55 yielding connection may be located at various points, but I have illustrated it as interposed between the gear 20 and the pinion 22. To this end the gear 20 is annular in form, and it has a conical inner surface 33 60 which engages a corresponding surface upon

a web or plate 34 integral with the pinion 32. A dished ring 35 is carried by the plate 34, this ring having a flange which engages the right-hand surface of the gear 20. Studs 36 screwed into the plate 34 pass loosely 70 through openings in the ring 35, and compression-springs 37, coiled around these studs, engage the ring and force it toward the plate 34, thus causing the flange 35 to press the gear in a direction to force the 75 conical surfaces into frictional engagement with each other. The strength of the springs 37 is so adjusted that the friction resulting from this arrangement is sufficient to cause the gear 20 to rotate normally in 80 unison with the pinion 22, while, on the other hand, the frictional connection will yield when the mechanism is subjected to any unusual strain, thus preventing sudden and severe reversal in the direction of rotation of the shaft 8 and the generator-shaft connected therewith. To afford convenient access to the friction-coupling just described, the casing 7 is provided with a removable screw-plug 38, through which access 85 may be had to the studs 36, so that they may be removed, when necessary, to replace or adjust the springs 37.

While the present invention is illustrated, and is particularly described, as embodied 95 in a mechanism in which the first pinion of the speed-reducing gearing is employed as the third rotary element for the purpose of controlling the action of the one-direction clutch through which the first rotary element rotates the second rotary element, the invention is not limited to this specific arrangement, nor is it necessarily embodied in a gearing of the general form and arrangement illustrated herein; but the invention 100 may be embodied in various other forms within its nature as defined in the following 105 claims.

I claim:—

1. Power-transmission mechanism having, 110 in combination, a first rotary element; a second rotary element; and connections, between said elements, through which the first rotary element may drive the second rotary element, and through which the second rotary element may drive the first rotary element in the same direction but at a reduced speed-ratio; said connections including a clutch operative in the normal direction of rotation of said elements, and a third rotary 115 element coaxial with one of the first two rotary elements and normally rotative therewith, but capable of a limited rotation relatively thereto, the third rotary element being connected with the clutch and adapted, 120 as a result of such relative rotation, to throw the clutch out of operation when the first rotary element is rotated in a reverse direction.

2. Power-transmission mechanism having, 130

in combination, a first rotary element; a second rotary element; and connections, between said elements, through which the first rotary element may drive the second rotary element, and through which the second rotary element may drive the first rotary element in the same direction, but at a reduced speed-ratio; said connections including a one-direction clutch adapted to permit one rotary element to overrun when driven by the other, a third rotary element coaxial with one of the first two rotary elements and normally rotative therewith, while capable of a limited rotation relatively thereto, and means, connected with the third rotary element and coöperating with said clutch, to throw the clutch into inoperative position, as a result of such relative rotation of the third rotary element, when the first rotary element is rotated in a reverse direction.

3. Power-transmission mechanism having, in combination, a first rotary element; a second rotary element; and connections between said rotary elements, through which the first rotary element may drive the second rotary element, and through which the second rotary element may drive the first rotary element in the same direction, but at a reduced speed-ratio; said connections including a roller-wedge clutch adapted to permit one rotary element to overrun when driven by the other, a third rotary element coaxial with one of the first two rotary elements and rotatable relatively thereto, and fingers projecting from the third rotary element into the path of movement of the rollers in said clutch and adapted to force the rollers to inoperative position, as a result of such relative rotation, upon a reverse rotation of the first rotary element.

4. Power-transmission mechanism having, in combination, a first rotary element; a second rotary element; means, including a one-direction clutch, through which the first rotary element may actuate the second rotary element; means, including speed-reducing gearing and a one-direction clutch, through which the second rotary element may actuate the first rotary element in the same direction of rotation; said means including also a third rotary element coaxial

with one of the first-mentioned two rotary elements and rotatable normally therewith, while capable also of a limited rotation relatively thereto; and means, connected with the third rotary element and coöperating with one of said clutches, for throwing said clutch into inoperative position, as a result of said relative rotation, when the first rotary element is rotated in a reverse direction.

5. Power-transmission mechanism having, in combination, a first rotary element; a second rotary element coaxial with the first; a one-direction clutch through which the first rotary element may drive the second, while the latter is free to overrun; gearing through which the second rotary element may drive the first, at a reduced speed-ratio but in the same direction, said gearing including a gear on the first rotatable element and a pinion journaled coaxially with the second rotary element but capable of a limited rotation relatively thereto; and means, connected with said pinion and coöperating with said clutch, for throwing the clutch into inoperative position, as a result of such relative rotation of the pinion, when the first rotary element is rotated in a reverse direction.

6. Power-transmission mechanism having, in combination, a first rotary element; a second rotary element coaxial with the first; a roller-wedge clutch through which the first rotary element may drive the second, while the latter is free to overrun; gearing through which the second rotary element may drive the first at a reduced speed-ratio but in the same direction, said gearing including a gear on the first rotary element and a pinion journaled coaxially with the second rotary element; and fingers projecting, from said pinion, into the path of movement of the rollers of said clutch and adapted to throw said rollers into inoperative position, as a result of relative rotation of said pinion and the second rotary element, when the first rotary element is rotated in a reverse direction.
